OTHER PUBLICATIONS

Office Action dated Jan. 30, 2018 issued in corresponding Brazilian design application No. 30-2017-002405-0, 3 pages, including English translation.

Primary Examiner — Barbara Fox*Assistant Examiner* — Kristin E Reed(74) *Attorney, Agent, or Firm* — Drinker Biddle & Reath LLP(57) **CLAIM**

The ornamental design for a reel for binding tool, as shown and described.

DESCRIPTION

FIG. 1 is a front, left perspective view of a reel for binding tool showing my new design;

FIG. 2 is a rear, right perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
FIG. 8 is a bottom view thereof.

1 Claim, 8 Drawing Sheets
